UNITED STATES PATENT OFFICE.

THOMAS E. MURRAY, OF NEW YORK, N. Y.

CRUDE-OIL STILL.

1,302,200.

Specification of Letters Patent. Patented Apr. 29, 1919.

Application filed November 7, 1916. Serial No. 129,923.

To all whom it may concern:

Be it known that I, THOMAS E. MURRAY, a citizen of the United States, residing at New York, in the county of New York and State of New York, have invented a certain new and useful Improvement in Crude-Oil Stills, of which the following is a specification.

The invention relates to a crude oil coking still, that is to say, a still in which the crude oil is distilled and the residue is reduced to a solid residue or coke, free from tar or other liquid matter, and more particularly to the removal of said coke from said still.

Heretofore the process of refining crude petroleum has been to convey it by suitable piping to a horizontal cylindrical receptacle set in masonry containing also a grate, fire-box and flues. The various products of distillation are given off in turn as the temperature increases. The solid residue being, however, deposited on the oil receptacle bottom, where it is exposed to the intense furnace heat, causes the burning out of said bottom. In order to remove the residue after the distillation is complete, the fire is drawn, and after the oil receptacle and masonry are cooled sufficiently to permit men to enter the receptacle through man-holes in its ends, the solid residue is manually shoveled out—a proceeding which wastes the time necessary for the cooling of the parts and renders the labor necessary for the removal of the residue both onerous and disagreeable.

In the present embodiment of my invention, I provide a construction which eliminates solid residue on the opposite side of the oil receptacle wall upon which the furnace gases impinge, by collecting the said residue in a receptacle which is located below the heated surface of the oil receptacle—or, in other words, which is below the fire grate surface. The preferred form of this receptacle here illustrated is elongated, with its ends extending through and protruding beyond the outside of the masonry. These ends may be opened and closed, so that the contents of the residue receptacle may be

removed without requiring the men to go inside the casing, much less inside the oil receptacle. Hence there is no necessity of reducing the temperature, and, therefore, there is a great saving of time. I also may provide in the residue receptacle a lining which can be readily removed together with all of the accumulated residue thereon, and which after dumping, can be replaced—another time saving operation.

In the accompanying drawings—

Figure 1 is a vertical section of my crude oil still. Fig. 2 is a horizontal section on the line x , x of Fig. 1. Fig. 3 shows in section similar to Fig. 1, a modified form of construction of the lower part of the oil receptacle.

Similar letters of reference indicate like parts.

A is the fire-grate, and B the fire chamber which communicates with an escape opening or stack C. D is a vertical cylindrical receptacle open at its lower end to register with an opening in the upper side of a horizontal receptacle E in which the solid residue of distillation is deposited. Said receptacle is placed below the fuel-receiving surface of the grate A; or, in other words, the heating surface of the oil receptacle D, which is above said residue receptacle E, is also above said grate. A masonry casing G incloses the receptacles and grate, and has a horizontal baffle-plate F disposed above said grate. The oil receptacle D passes through said plate F, and, as here shown, closes an opening H in the top wall of the casing. Through opening H pass the crude oil supply pipe I and the pipe J which leads from the oil receptacle to the condenser, not shown. The baffle-plate F does not extend entirely across the casing G, so that a gas passage K is left between the edge of said plate and said casing. The gases in circulating take the course shown by the arrows in Fig. 1, first, meeting the oil receptacle below said plate F and passing around said receptacle, then rising through said passage K, and then moving in the reverse direction, passing around the receptacle above plate F to

the escape opening or stack at C. The whole wall of the oil receptacle above the grate is thus heating surface, while the residue receptacle below the grate is screened by said 5 grate and the fuel thereon, so that said residue receptacle is not heated by gas current due to combustion of fuel on the grate, as shown by the arrows in Fig. 1. Instead of producing the gas current by the consumption 10 of solid fuel on the grate, I may substitute any suitable form of gas or oil burners, but in that case for the grate A a solid screen should be substituted, or if the grate be retained, the interstices between the bars 15 should be closed.

The receptacle E, as here shown, is substantially semi-cylindrical in cross section, with its flat side uppermost, and is supported by brackets L resting on masonry blocks M. Its ends extend through opposite walls of casing G, as shown in Fig. 2. Each end is here provided with means for opening and closing—said means being here a cover plate N, secured in place by removable 20 bolts. Each cover plate N is suspended by a chain O from a crane P pivoted on the outer wall of the casing. By removing the bolts, a cover plate N (or both plates) may be swung outwardly to permit of access to 25 the interior of the residue receptacle. Within the curved bottom of said receptacle I may place a removable lining R preferably of steel or other suitable metal. There is a 30 fire-grate opening, an ashpit opening and a cleaning opening in the casing G—these 35 openings being respectively provided with suitable doors S, T, U.

The operation is as follows:

The receptacle D being filled with crude 40 oil, and fire started on the grate A, the various products of distillation are given off as the temperature rises. The solid residue meanwhile descends and accumulates in the receptacle E, as shown in Fig. 1. When the 45 distillation is finished, the fire is banked, and either cover plate N, or both of said cover plates, may be removed, if desired. The solid residue is then removed from the 50 receptacle E by any suitable manually operated implements. Where a removable lining R is used in the said receptacle, said lining may be withdrawn by sliding the same longitudinally out of an open end of the 55 said receptacle, so that it will bring with it the accumulated deposit. After this deposit is dumped, the lining may be replaced.

It will be observed—

(1) That there is no solid matter on the 60 opposite side of any part of the oil receptacle wall upon which part the fire gases directly impinge. Hence there is no part of the oil receptacle wall liable to be burnt out by said impinging gases.

(2) That the uprising gas current passes around, first, the lower portion and then the 65 upper portion of said oil receptacle, thus effectively heating the contents thereof.

(3) That all of the solid residue is collected in the receptacle E, which is below the level of the fire-grate A and hence is 70 screened by said grate from impact of the gas current, and therefore is comparatively cool.

(4) That the ends of residue receptacle E extend outside of the casing walls, so that 75 those who remove the deposit do not have to enter the casing, and there is no need of reducing temperature during said removal—thus materially saving time.

(5) The oil receptacle can, and should be, 80 so proportioned as that the whole residue from a given charge will form below the line of fire contact with said receptacle.

If it is not desired to use a separate receptacle for the residue deposit, I may receive 85 the same upon a hinged cover W which closes the oil receptacle bottom. Said receptacle may then be supported on standards V (one shown in Fig. 3) and said cover W may be normally held closed by a chain and 90 drum Y. The cover W may be dropped, as shown in dotted lines Fig. 3, to dump the deposit thereon, which deposit may then be manually removed through the casing opening closed by door U. 95

I claim:

1. A coking still for crude oil, comprising a vertical tubular receptacle for said oil open at its lower end, a receptacle for coke disposed directly below said oil receptacle 100 and having in its upper side an opening registering with said open end of said oil receptacle, and means disposed above said coke receptacle for heating said oil receptacle; the said coke receptacle being of elongated 105 form and protruding through a wall of a casing, and a removable closure being on said protruding end.

2. A coking still for crude oil as in claim 1, the said coke receptacle being of elongated form and protruding at its ends through opposite walls of said casing, there being a removable closure, as set forth, on each of said protruding ends. 110

3. A coking still for crude oil as in claim 115 1, the said coke receptacle being of elongated form and protruding through a wall of said casing, and the said removable closure being a cover plate on said protruding end, and, combined therewith, a crane pivoted on said casing, from which crane said cover plate is suspended, the said crane being pivoted on said casing and supporting said cover plate when said plate is removed from said residue receptacle. 120

4. A vertical coking oil still, a horizontal 125

tubular receptacle for non-volatile residue disposed below said still and communicating therewith, a trough-shaped longitudinally slidable lining of refractory material in said 5 receptacle, a removable cover for an end of said receptacle, and means disposed above said receptacle for heating said still.

In testimony whereof I have affixed my signature in presence of two witnesses.

THOMAS E. MURRAY.
